[57] CLAIM

The ornamental design for a multiple cuvette assembly, substantially as shown and described.

DESCRIPTION

FIG. 1 is a top perspective view of a multiple cuvette assembly, showing my new design;

FIG. 2 is a bottom perspective view thereof;

FIG. 3 is a right-side elevation view thereof;

FIG. 4 is a front-end elevation view thereof;

FIG. 5 is a rear-end elevation view thereof;

FIG. 6 is a left-side elevation view thereof;

FIG. 7 is a bottom plan view thereof;

FIG. 8 is a top plan view thereof; and

FIG. 9 is a cross-sectional view along lines 9—9 of FIG. 8 illustrating the "U" shape of the cuvettes in the assembly.

FIG. 9

FIG. 8

FIG. 5

FIG. 6
